CLAIM

The ornamental design for a personal care packaging, as shown and described.

DESCRIPTION

FIG. 1 is a top, front and side perspective view of the personal care packaging thereof in accordance with our new design; FIG. 2 is a front elevational view of the personal care packaging thereof;

FIG. 3 is a rear elevational view of the personal care packaging thereof;

FIG. 4 is a side elevational view of the personal care packaging thereof;

FIG. 5 is a side elevational view of the personal care packaging thereof;

FIG. 6 is a top perspective view of the personal care packaging thereof; and,

FIG. 7 is a bottom perspective view of the personal care packaging thereof.

The broken lines are directed to environment and are for illustrative purposes only.

The broken lines form no part of the claimed design.

1 Claim, 3 Drawing Sheets
